UNITED STATES PATENT OFFICE.

DANIEL L. CHANDLER, OF AYER, MASSACHUSETTS.

BRUSH-MAKING MACHINE.

1,084,536.

Specification of Letters Patent. Patented Jan. 13, 1914.

Application filed May 15, 1912. Serial No. 697,366.

To all whom it may concern:

Be it known that I, DANIEL L. CHANDLER, a citizen of the United States, residing at Ayer, in the county of Middlesex and State 5 of Massachusetts, have invented new and useful Improvements in Brush-Making Machines, of which the following is a specification.

This invention relates to brush making 10 machines.

The object of the invention is to provide a machine by which bunches of bristles may be selected from a mass of bristles and inserted in holders to form tufts and subsequently to 15 force the holders containing said bristles into a brush-stock which has previously been provided with the required number of holes adapted to receive said bristle tufts.

In the attainment of the above object the 20 bristles are selected in a predetermined quantity from the mass of bristles, doubled to form a loop and the loop inserted in one of said holes in said brush-stock, pushed through said stock and into the end of a 25 tube which has previously been chamfered and moved into alignment with the hole in said brush-stock through which said loop has been inserted. The tube is then compressed to bind said bristles therein and the portion 30 thereof containing said loop is cut off and forced into the hole containing said tuft of bristles.

The object is further to provide means adapted to hold and automatically move said 35 brush-stock longitudinally and transversely to bring each of the holes therein into alignment with said tuft inserting means.

A further object is to provide means adapted to automatically discontinue the 40 operations of said machine upon the insertion of a predetermined number of tufts into a brush-stock.

A still further object is to provide means 45 adapted to insure a perfect alignment of the tube and tube forcing means with their respective coöperating mechanisms.

With these ends in view, my invention consists in certain features of novelty in the 50 construction, combination and arrangement 50 of parts by which the said objects and certain other objects hereinafter appearing are attained all as fully set forth in the following specification and particularly pointed out in the claims.

55 Referring to the drawings: Figure 1 is a plan view of a brush making machine em-

bodying my invention. Fig. 2 is a front elevation of the machine. Fig. 3 is a side elevation of the machine as viewed from the right of Fig. 2. Fig. 4 is a detail section, 60 partly in elevation, taken on line A—A of Fig. 1. Fig. 5 is a detail front elevation of the tube compressing dies with parts of the actuating mechanism therefor broken away to save space in the drawing. Fig. 6 is a 65 detail sectional view taken on line B—B of Fig. 4. Fig. 7 is a sectional elevation taken on line C—C of Fig. 1. Fig. 8 is an enlarged detail elevation, partly in section, 70 showing a portion of the bristle feeding and tuft forming mechanism shown in Fig. 7 with one plate of the bristle carrier removed. Fig. 9 is a detail elevation of a portion of the actuating means for feeding the brush-stock relatively to the tuft inserting means 75 with a portion of the stop mechanism shown in connection therewith. Fig. 10 is a sectional view taken on line D—D of Fig. 1. Fig. 11 is a detail view taken on line E, E of Fig. 9. Fig. 12 is a plan view of the clutch 80 mechanism. Fig. 13 is a side elevation of the mechanism illustrated in Fig. 12 with the driving pulley therefor shown dotted. Fig. 14 is a sectional elevation taken on line E—E of Fig. 1. Fig. 15 is a detail plan section 85 illustrating the action of the needle and bristle carrier inserting the tuft through a brush-back and into the end of the tube. Fig. 16 is a detail plan view similar to Fig. 15 illustrating the action of the dies for compressing and indenting the tube together with the saw for cutting off the tube. Fig. 17 is a detail plan section illustrating the action of the mechanism for forcing the cut off portion of the tube into the brush-stock. 90 Fig. 18 is an enlarged sectional view taken on line G—G of Fig. 7. Figs. 19 and 20 are elevations of two forms of brush-stocks adapted to have bristle tufts inserted therein by the machine embodied in this invention. 100 Fig. 21 is a section taken on line H, H of Fig. 9. Fig. 22 is a perspective view of one form of brush produced by the machine.

Like numerals refer to like parts throughout the several views of the drawings. 105

In the drawings 21 is a main driving shaft journaled in suitable bearings 22 and 23 on a base or frame 24 and having a clutch pulley 25 secured thereto adapted to be connected to and disconnected from said driving shaft 110 21 by the clutch actuating means herein-after described. From the shaft 21 most

of the mechanisms of the machine receive their power.

Bristle feeding and tuft forming mechanism. (See Figs. 1, 7, 8 and 18.)—A hopper 26 for the bristles preferably consists of two walls 27 and 28 provided, respectively, with grooves 29 and 30 constituting ways to receive a weight 31 arranged to slide vertically therein and which serves to crowd the bristles downwardly in said hopper. The hopper has a back wall 32 and the mass of bristles is inserted in the hopper, as shown in Fig. 18, it being understood, however that when the hopper is loaded, it will be loaded with a greater mass of bristles than is shown in the drawings. A fourth wall 33 serves to confine the ends of the bristles at that side and is preferably removable in order to facilitate the introduction of the mass of bristles. The hopper 26 which is otherwise open at the bottom is provided with two downwardly curved depending guides 34 and 35 so shaped as to guide the bristles to the lowermost point thereof where they are to be engaged by the feeding devices. The bottom of the weight 31 is preferably provided with a V-shaped notch 36 so formed as to facilitate the crowding of the bristles toward the lowermost point 30 of the guides 34 and 35.

The lowermost bristles of the mass in the hopper rest upon a bristle carrier 37 in the manner shown in Figs. 7, 8 and 18. This bristle carrier preferably consists of two plates 38 and 39 separated by a space in which is located a plate 40 carrying at its upper portion a very thin plate or needle 41 provided at its forward end with a notch or recess 42 designed to engage the bristles as they are crowded down into a recess or throat 43 provided in the upper side of the plates 38 and 39 of the bristle carrier 37. Preferably, the size of this recess or throat is varied by means of two adjustable plates 44 and 45, see Figs. 7 and 8, secured to opposite sides of the bristle carrier 37. The bristle carrier 37 is provided with a longitudinal passage 46, preferably cylindrical in form, communicating with the recess or throat 43 and also communicating with a slot 47 in which the needle 41 reciprocates, said needle also extending up into said cylindrical passage, as clearly shown in Fig. 18.

The plates 38 and 39 which constitute the bristle carrier 37 are secured to a slide 48 mounted to slide on a suitable guide 49 provided on a bracket 50 mounted on the base of the machine. This slide is reciprocated at the proper times in the operation of the machine by a cam 51 secured to the shaft 21 and having a groove 52 in which is located a cam roll 53 journaled on the slide 48. The plate 40 is secured to a slide 54 mounted to slide in suitable ways provided

in the slide 48 and the slide 54 is reciprocated at the proper times in the operation of the machine by means of a cam 55 secured to the shaft 21 and having a groove 56 in which is located a cam roll 57 journaled on the slide 54.

In the operation of the bristle feeding and tuft forming mechanism, the needle 41 is first advanced past the recess or throat 43 and in so doing said needle engages a number of bristles located in said recess, and in advancing beyond said recess, said needle doubles the bristles transversely thereof and forces them into the cylindrical passage 46, thus forming a tuft *c* having a loop *d* engaged by the needle. The tuft thus formed is carried forward to a point adjacent to the end or nose of the bristle carrier 37, said bristle carrier is then advanced to a point adjacent to the holder into which the bristles are to be inserted, as will appear more fully hereinafter, and then the needle 41 is advanced within the bristle carrier to carry the tuft out of the bristle carrier into the bristle holder.

Tube feeding mechanism. (See Figs. 1, 2, 3, 10 and 14.)—A suitable metallic tube 58 passes between a pair of feed rolls 59 and 60 secured to shafts 61 and 62, respectively, the latter shaft being journaled in suitable bearings 63 and 64 provided on a slide 65 mounted to slide transversely of the longitudinal dimension of the tube 58 in ways 66 provided on a bracket 67 secured to the base 24. The shaft 61 is journaled in bearings 68 and 69 mounted to slide vertically in ways 70 and 71 provided on the slide 65. Suitable compression springs 72 and 73 provided with adjusting screws 74 and 75, respectively, urge the bearings 68 and 69 downwardly, thus causing the feed roll 59 to press the tube 58 against the feed roll 60 and assuring sufficient frictional engagement so that the tube may be properly fed when the shafts 61 and 62 are rotated. The shafts 61 and 62 are preferably geared together by gears 76 and 77 secured to said shafts, respectively, and meshing with each other, thus causing said shafts to be rotated in unison and the feed rolls 59 and 60 to be positively rotated at the same speed. At the proper times in the operation of the machine, the feed rolls 59 and 60 are rotated to intermittently feed the tube 58 longitudinally by suitable mechanism. Preferably, this mechanism comprises a ratchet 78 having a hub 79 journaled in a suitable bearing provided in a bracket 80 and held against longitudinal movement therein by a collar 81 secured to said hub. The ratchet 78 is provided at its opposite side with a hub 82 upon which a pawl carrying lever 83 is mounted to rock and is held against longitudinal movement by a collar 84 secured to said hub.

Mounted upon the pawl carrier 83 is a feed pawl 85 engaging the teeth of the ratchet 78, see particularly Figs. 1 and 3, arranged to drive said ratchet in one direction, while a stop pawl 86, see Figs. 1 and 10, pivoted upon the bracket 80 engaging said ratchet prevents a reverse rotation thereof. The pawl carrier 83 is rocked at the proper times in the operation of the machine by a slide 87, see Figs. 1 and 3, connected at its forward end to said pawl carrier by a pivot 88 and having its rear end mounted to slide in a suitable guide 89. The slide is reciprocated by a cam 90 having a groove 91 in which is located a cam roll 92 journaled on said slide.

At certain times in the operation of the machine, the tube is moved from right to left, Fig. 1, in order to present the end of 20 the tube first to the action of a bur-removing or chamfering means and then to the action of dies for compressing the walls of the tube, as will appear hereinafter.

In order that the tube may be properly 25 guided and held at that end which is to be operated upon by these instrumentalities, there is provided a guide 93, (see particularly Fig. 1,) secured to the slide 65. It will be evident that since the slide 65 is to 30 be moved to carry the feed rolls 59 and 60 to and fro from right to left and vice versa, there must be provided a sliding connection between the shaft 62 and the ratchet 78 and to this end said ratchet is provided with a 35 feather 94 arranged to slide in the key-way 95 provided in said shaft.

The slide 65 is reciprocated by mechanism 40 preferably comprising a link 96 pivotally connected at one end to said slide and at its other end to the rocker arm 97, see Fig. 2, secured to a rock shaft 98. This rock shaft, which is journaled in suitable bearings 99 on the base 24, is rocked at the proper times in the operation of the machine 45 by a cam 100 secured to the shaft 21 having a groove 101 in which is located a cam roll 102 journaled on an arm 103 secured to said rock shaft.

Tube chamfering or bur-removing mechanism. (See Figs. 1, 3 and 18.)—In order 50 that the bur may be removed from the previously cut end of the tube 58 there is provided a suitable rotating chamfering tool 104 suitably shaped to bevel or chamfer the inside of the end of the tube. This tool is 55 suitably mounted or secured in the end of a shaft 105 journaled in suitable bearings 106 and 107 on a slide 108 mounted to slide on suitable ways 109 on the bracket 50, see Fig. 18. At the proper time in the operation 60 of the machine, the slide 108 is carried forward and back to carry the chamfering tool toward and away from the end of the tube, by means of a cam 110 secured to the 65 shaft 21 and having a groove 111 in which

is located a cam roll 112 journaled on said slide. The shaft 105 is rotated by means of a belt passing around a pulley 113 secured to said shaft.

Tube compressing and indenting mechanism. (See Figs. 1, 2, 5, 14, 15, 16 and 17.)—After the bur has been removed from the end of the tube by chamfering the same, as hereinbefore described, the tube is carried from the position shown in Fig. 1 to- 70 ward the left, a longitudinal feeding movement is imparted thereto to bring the same into the position shown in Fig. 15, and the tuft is then inserted into the chamfered end of the tube in the manner shown in said 75 figure by advancing the needle 41 into the position shown, into the tube. After this has taken place, the end of the tube containing the tuft of bristles is compressed and indented by the following mechanism.

Referring now to Fig. 5, it will be observed 80 that grouped about the end of the tube 58 there is a plurality of dies for accomplishing the compressing and indenting of the tube, these dies being preferably four in 85 number arranged in pairs, one pair consisting of the members 114 and 115 and the other pair consisting of the members 116 and 117, all of which are mounted to slide radially in a circular die holder or support 90 95 118 and are given said sliding movement by means of a ring 119 swivaled upon said die holder. This ring carries a plurality of arms 120, 121, 122, and 123 and pivoted to the outer ends of the dies 114, 115, 116, and 100 117, respectively, as shown in Fig. 5. As this ring is rocked to and fro on the stationary die holder 118 by a mechanism which will be described hereinafter, the swinging arms just described act to impart to their 105 respective dies a simultaneous movement toward the tube and away from the tube. The extremities of the dies where they engage the tube are substantially cylindrically formed. Preferably the die members 116 110 and 117 are provided, respectively, with spurs 124 and 125 which indent the tube and form indentations 126 and 127 extending into the loop of the tuft in the manner illustrated in Fig. 22, thus locking the tuft 115 within the tube. It is also highly desirable that the holder shall be compressed around that portion which is located between the indentations 126 and 127 and the end of the tube from which the bristles project and 120 to this end the die members 114, 115, 116 and 117 are provided, respectively, with more or less abrupt shoulders 128, 129, 130 and 131, as best illustrated in Figs. 15, 16 and 17, these shouldered portions of the dies 125 serving to form a reduced portion or neck 132 firmly gripping the bristles adjacent to that end of the holder or tube from which they project. Thus the entire operation of compressing the holder or tube and indent- 130

ing the same is simultaneously accomplished by the simultaneous action of all four of the die members.

The die actuating ring 119 is rocked to and fro by any suitable means and for this purpose I preferably provide said ring with a depending arm 133 connected by a link 134 to a rocker arm 135 secured to a rock shaft 136 journaled in bearings 137 on the base 24.

10 A rocking motion is imparted to the rock shaft 136 by means of a cam 138 secured to the shaft 21 and having a groove 139 in which is located a cam roll 140 journaled on an arm 141 secured to said rock shaft.

15 *Tube cutting off mechanism.* (See Figs. 1, 2 and 14.)—After the bristles have been inserted in the end of the tube and the end of the tube has been compressed and indented, as just described, that portion of the

20 tube which contains the bristles is cut off of the remainder of the tube by suitable means preferably consisting of a circular saw 142 which is placed adjacent to the front face of the dies and the die holder.

25 This saw is secured to the shaft 143 journaled in a suitable bearing provided in a rocker arm 144 secured to a rock shaft 145 mounted in suitable bearings 146 on the base 24. The shaft 143 has secured thereto a

30 spur gear 147 meshing into an intermediate gear 148 rotatably mounted upon the arm 144, said gear in turn meshing with a gear 149 secured to a shaft 150 also journaled in the rocker arm 144 and having secured there-

35 to a pulley 151 driven by a belt 152 from overhead. The saw is carried to and fro across the path of the tube 58 at the proper times in the operation of the machine by a cam 153 secured to the shaft 21 and having

40 a groove 154 in which is located a cam roll 155 journaled on an arm 156 secured to the rock shaft 145.

By the mechanism just described, the tube is severed, thus leaving a portion thereof 45 forming a holder in which the bristles are firmly secured, the remainder of the tube being returned to its initial position to be operated upon by the bur-removing or chamfering mechanism while said cut off portion 50 or holder is acted upon by mechanism hereinafter described.

Brush-stock holder and actuating mechanism therefor. (See Figs. 1, 2, 3, 4, 9 and 14, referring particularly to Figs. 4 and 55 14.)—The circular die holder or support 118 which is secured or supported upon the bracket 50 has extending horizontally therethrough a recess or rectangular slot 157 and in which is mounted a brush-stock

60 holder, preferably consisting of a slide 158 having a slot 159 extending longitudinally of said slide 158, and provided with grooves 160 upon opposite sides of said slot said

65 grooves 160 being formed preferably to correspond with the opposite edges of a

brush-stock 161 substantially equal in length to the body portion 162 of said brush-stock. The slot 159 extends longitudinally of the slide 158 terminating at 163, said terminating point thereof being preferably at 70 one side of a point on said slide through which the axis of the cylindrical die 118 passes while said slot 159 extends to the end of said slide 158 upon the opposite side of said point from that upon which the end 163 is located, thus permitting the brush-stock 161 to be inserted into said slot between the grooves 160 against the end 163 of said slot, the slide 158 being but slightly thicker than the brush-stock 161. The slot 159 is 75 made long for the purpose of receiving a brush-stock having a handle attached thereto as illustrated in Fig. 19 and a clamping slide 164 provided with a recess 165 which is adapted to receive the end of said handle 80 and center the same in said slot 159 relatively to the body 162 of said brush-stock. The slide 164 is provided with tongues 166 which extend longitudinally thereof for a portion of its length which engage and are 85 guided by grooves 167 formed in opposite walls of said slot 159. A thumb screw 168 has screw-threaded engagement with said slide and is adapted to engage a cross piece 169 which connects the outer ends of the 90 slide 158 to prevent spreading thereof, said screw 168 being for the purpose of clamping said slide within said groove to secure said brush-stock against the end 163 of said slot.

When it is desired to hold a brush-stock of the character illustrated in Fig. 20, a filler 170 is employed having a tapped hole 171 adapted to receive the screw-threaded end 172 of said brush-stock, said filler being 100 substantially equal in length to the handle of the brush-stock illustrated in Fig. 19. The slide 158 which constitutes the holder for said brush-stock is mounted for a longitudinal sliding movement in a holder 110 slide 173, the opposite faces of which bear against opposite faces of the rectangular slot 157, provision being made in said slot to permit of a substantial movement of said slide 173 transversely of said slide 158, said 115 slide 173 being guided in said transverse movement by pins 174 and 175 upon opposite edges of said slide respectively which move in guides 176 and 177 respectively in said cylindrical holder, suitable clearance 120 being provided in the ring 119 to permit the same to be rocked without interfering with said slide 173 or said pin 175.

By reference to Fig. 14 it will be seen that the slide 158 is arranged at one side of 125 the center of the holder slide 173, thus bringing the face 178 of said slide 158 in alignment with the face 179 of the slide 173 and against the partition 180 of said cylindrical holder. Said partition 180 is preferably 130

very thin and not only constitutes a guide for said slides but the opposite face thereof constitutes a guide for the dies 114, 115, 116 and 117. A cylindrical hole or guide-way 181 is provided in said partition concentric with the axis of said cylindrical die and of sufficient size to admit the end of the tube 58. It will also be seen by reference to said Fig. 14 that the body portion 162 of the brush-stock 161 is held within the holder 158 in close proximity to said hole 181.

The form of brush-stock illustrated in Figs. 19 and 20 is provided with a plurality of series of holes 182 preferably arranged in parallel with each other and so arranged in said holder that one of said holes 182 will be in alignment with the center of said hole 181, the hole "a" in Fig. 4 being in alignment therewith in the present instance. The slide 158 is moved longitudinally in the slide holder 173 to bring the holes 182 successively into alignment with the hole 181 at the proper times in the operation of the machine by a cam 183 having a cam groove 184 in which is located a cam roll 185 pivotally mounted upon a cam slide 186 adapted to slide in a guide 187 and pivotally connected to the slide 158, which for the purpose of adjustment and to properly align holes in brush-stocks of various sizes with the hole 181 is provided with an adjustable connection 188.

A transverse movement is imparted to the holder slide 173 and consequently to the brush-stock 161 to bring the several parallel series of holes successively into alignment with the center of the hole 181 at the proper times in the operation of the machine, by a cam 189 having a cam groove 190 in which is located a cam roll 191 pivoted upon the end of a lever 192, the lever 192 being pivoted at 193 in a bracket 194 secured to the base 24, said lever 192 being pivotally connected at 195 to the pin 175 by an adjustable link 196.

The cams 183 and 189 are secured to the end of a shaft 197 journaled in bearings 198 on the base 24, said shaft having a suitable intermittent rotary motion imparted thereto by suitable mechanism preferably consisting of a pawl and ratchet feed mechanism 199, see Figs. 1 and 9, said mechanism consisting of a ratchet disk 200 provided with teeth 201 adapted to be engaged by a pawl 202 pivotally mounted upon the end of a rocker arm 203, said rocker arm being pivotally mounted upon the shaft 197 inside of said disk 200, said disk being located at the end 60 of said shaft in order that it may be easily removed when it is desired to replace the same by a disk having a greater or less number of teeth thereon. A rocking movement is imparted to the rocker arm 203 to feed 65 said ratchet disk by a rod 204 slidably

mounted in a bearing or guide 205 upon the stationary bracket 50, said rod being engaged by a cam 206 which is secured upon the slide 48, operated as hereinbefore described, to move the bristle carrier 37. Thus, 70 it will be seen that for each movement of said bristle carrier to form a tuft of bristles said disk 200 will be rotated one tooth thereby rocking the shaft 197 and consequently 75 moving the slide 158 longitudinally a distance equivalent to the distance between the centers of two successive holes. As the slide 48 recedes withdrawing the cam 206 from the end of the rod 204, a spring 207 returns the rocker arm 203 and the pawl 202 to their 80 initial positions to engage another of the teeth 201; said disk 200 is prevented from being rotated in a reverse direction during the return movement of the pawl 202 by a stop pawl 208. To insure the stopping of 85 said ratchet disk 200 at the completion of the movement of the rocker arm 203 and to check the movement of said brush-stock I have provided a frictional device 209 secured to one of the bearing brackets 198 and 90 95 said frictional device being shown in section in Fig. 21.

It will be observed by referring to Figs. 19 and 20 that each brush-stock shown in 95 said figures is provided with thirty-one holes arranged in three parallel series. Assuming that the brush is located in the same relation to the hole 181 as that shown in Fig. 4 the mechanism which feeds said brush- 100 stock must be arranged to feed the same longitudinally step by step until each hole in the series of holes in which the hole "a" is located has been acted upon, as will be hereinafter described, whereupon said brush is 105 moved transversely to bring the second of said series of holes into alignment with the hole 181. Said brush must then be moved longitudinally thereof until each of these 110 holes has been acted upon when the final series of holes will be brought into alignment with said hole 181 as have been the two other series of holes, and at the completion of said last series of holes the machine will be stopped as hereinafter described. 115

When it is desired to insert bristles in brush-stocks of a different design and with a different number of holes therein a holder of a suitable size is provided and inserted in place of the holder 158, and the cams 183 and 189 and disk 200 are all replaced by cams of the proper design and a disk with the proper number of teeth thereon, different sizes of which are held in readiness to be used for the different size brush-stocks 120 into which it is desired to insert bristles, it being understood that the cam 206 has a sufficient throw to accommodate the different throws required.

Tube inserting mechanism and lock. (See 130)

Figs. 1, 2, 3, 14, 15, 16 and 17, particularly Figs. 1, 2 and 14.)—Following the chamfering of the tube 58, as hereinbefore described, said tube is fed from the tube chamfering means by the movement of the slide 65 toward the left in Fig. 1 and the end of said tube is presented to the brush-stock 161 between the dies 114, 115, 116 and 117 up to and into alinement with the hole 181. The 10 needle 41 is then advanced within the bristle carrier 37 and the loop *d* of the bunch of bristles carried thereby is inserted through the hole "a" and into the end of said tube 58 after which said needle is withdrawn and 15 the compressing dies 114, 115, 116 and 117 are actuated to compress the end of said tube against said bristles, as hereinbefore described. The saw 142 is then brought into action to cut off the end of said tube containing 20 said bristles after which it recedes to the position illustrated in Fig. 14 and the dies 114, 115, 116 and 117 are withdrawn to the positions shown in Fig. 5, thus leaving said tuft supported within the hole "a" in 25 readiness for the holder 212 to be forced into said hole.

It will be observed that the holes 182 are tapered or in other words the ends of the holes into which the tufts of bristles are inserted are smaller in diameter than at the 30 opposite end of said holes or at the side of said brush-stock upon which said holder 212 is compressed. It will also be noted that said holes are identical in shape with said holder after said holder has been compressed.

Secured to the slide 65 is a bracket 213 having a guide 214 adapted to guide a driver bar 215, said driver bar having a reduced 40 end 216 preferably of the same diameter as the tube 58. A rod 217 is slidably arranged in guides 218 formed in said bracket 213, and adapted to impart a reciprocatory motion to said driver bar 215 through the arm 45 219. Said rod 217 is adapted to be actuated to move said driver bar toward said brush-stock by an arm or actuator 220 secured upon a rock shaft 221 journaled in bearings 222 in the base 24, while a movement of said 50 driver bar away from said brush-stock is imparted thereto by a spring 223 engaging at one of its ends one of the guides 218 and at its opposite end a collar 224 which is secured to said rod 217.

The driver bar 215 as illustrated in Figs. 51 and 14 is in alinement with the hole 181 and the tuft feeding needle 41 and at the proper times in the operation of the machine said driver bar is reciprocated in the guide 60 214 and engages the end of the cut off portion 212 of said tube and forces the same through the guideway 181 and into the hole in which the tuft of bristles within said holder is located, by suitable means preferably consisting of a cam 225, see Fig. 1, hav-

ing a cam groove 226 in which is located a cam roll 227 journaled to rotate upon the end of a slide 228, said slide being arranged to slide in a guide 229 adjacent to said cam and connected at its opposite end to a rocker 70 arm 230 fast upon said rock shaft 221. As hereinbefore stated the bracket supporting said driver bar is mounted upon the slide 65 and as said slide 65 is moved from left to right, Fig. 1, to present the tube 58 first to 75 the chamfering tool 104 and then between the compressing dies or into alinement with the bristle tuft forming means, said driver bar 215 will be moved from its position shown in Fig. 1 to the left and out of range 80 with the actuator 220, or in other words, said tube feeding means and said tube forcing means will be alternately moved into alinement with the holes 181 or with the axis of the cylindrical support 118. The 85 end of the rod 217 is preferably provided with an adjusting means comprising a screw 231 having screw-threaded engagement with the end of said rod and the check nut 232, the head of said screw 231 being arranged to be engaged by the upper end of the rocker arm 220 when said driver bar is in alinement with the hole 181. The collar 224 is provided with an extension having a lug 233 adapted to be engaged by the upper 95 end of the rocker arm 220 to insure the return of said driver bar to its outer position, upon the completion of its holder inserting movement, in case the spring 223 fails to work.

To insure a proper or perfect alinement between the driver bar 215 and the hole 181 and the tube 58 and its chamfering tool 104, a rocker arm 234 is provided which is secured to the shaft 221 and has at its upper 105 end a tongue 235 which alines with a complementary slot 236 formed in a plate 237 secured to the slide 65, the corners of said plate being slightly beveled at the opposite sides of said slot to insure the entrance of 110 said tongue therein. A second slot 238 is provided in said plate 237 and upon the movement of the slide 65 to the left to bring the tube 58 into alinement with said tube inserting means said slot 238 will be brought 115 into alinement with the tongue 235 and upon the rocking of the shaft 221 said tongue will enter one or the other of said slots and if there happens to be any wear between the cam groove and the cam roll, or the connections between said slide 65 and said actuating means and said means fail to properly center or aline said several instrumentalities, the movements of said slide will be completed by the engagement of said tongue 120 with said slots.

Stop mechanism. (See Figs. 1, 9, 12 and 13.)—In a machine of this character it is essential that upon the completion of the bristle tuft inserting operations and after 130

all the holes in said brush-stock have been filled, the machine should be immediately brought to a stop and to accomplish this the following mechanism is preferably employed. The clutch pulley 25 is rotatably mounted upon the shaft 21 and has secured to the hub thereof a ratchet 239 which rotates against a disk 240 while said pulley is retained on said shaft by a collar 241. The disk 240 is secured to the driving shaft 21 and has pivotally mounted at 242 a lever 243 having a tooth 244 adapted to engage the teeth of the ratchet 239, said tooth being normally retained in engagement with said ratchet by a spring 245, see particularly Figs. 2, 12 and 13. The opposite end of the lever 243 from that upon which the tooth 244 is located is adapted to be engaged by a projection on a bell crank lever 246 pivotally mounted at 247 to a portion of the frame, said lever 246 being held in its normal position, as illustrated in Fig. 13, and against a stop 248 by a spring 249 engaging a pin 250. It will be seen by reference to this figure that the tooth 244 is out of engagement with the teeth 239 with the opposite end of the lever 243 engaging a projection on the lever 246 and also engaging a stop pin 251 on the disk 240. Thus it will be seen that said disk 30 and shaft 21 are prevented from rotating while the ratchet 239 is permitted to rotate freely upon said shaft. When it is desired to connect said shaft with said pulley 25 to start the machine into operation, the bell crank lever 246 is moved in the direction of the arrow "b" by any suitable means, preferably by the depressing of the treadle rod 252, whereupon the lever 243 will be released and the spring 245 will force the tooth 244 into engagement with the teeth upon the ratchet 239, thus causing the shaft 21 to be rotated until said teeth have been again disconnected.

Upon the movement of the lever 246 in the direction of the arrow "b" the pin 250 will be moved to the right in Figs. 12 and 13 slightly depressing the toothed end 253 of a lever 254 secured to the rock shaft 255 journalized in bearings 256 in the base 24. As said pin 250 is advanced beyond the tooth 253, the spring 257 returns said lever 254 and tooth 253 to its normal position whereupon said pin will engage said tooth upon the release of said treadle rod 252 and with hold the projection on the lever 246 from entering the path of the outer end of the lever 243, thus permitting the tooth 244 to remain in engagement with the ratchet 239.

The rock shaft 255 has upon its opposite end a rocker arm 258, see Figs. 9 and 11, having at its upper end an inclined tooth 259 which is adapted to be engaged when it is desired to stop the machine, by projections 260 suitably arranged upon one face of the ratchet disk 200 and by reason of said

engagement the lever 258 is rocked, thereby rocking the shaft 255 and the lever 254 to release the pin 250, thus permitting the projection on the lever 246 to move into the path of the outer end of the lever 243 and cause said lever to be rocked upon its pivot 242 until said lever engages the stop pin 251, thereby disconnecting the shaft 21 from its driving pulley and effectually stopping the rotation of said shaft. 75

It will be noted that in Fig. 9 the disk 200 is provided with two projections 260, thus the machine will be automatically stopped twice during one rotation of said disk, consequently two brush-stocks are 80 adapted to be filled with tufts of bristles during said rotation. It will also be obvious that by rearranging the teeth upon the ratchet disk 200 and the cam grooves in the cams 183 and 189 to correspond with the rearrangement of said teeth that a greater or less number of said stops 260 may be employed upon the face of said disk to be acted upon during one rotation thereof. 85

The general operation of the machine 90 hereinbefore described is as follows: The tube is first presented to the action of the bur-removing or chamfering mechanism. The inside of the end of the tube is chamfered, the tube is then carried into a position between the dies and into alignment with the hole 181, one of the holes in the brush-stock and also into alignment with the tuft inserting mechanism. A set of bristles 95 is then taken from the mass in the hopper and bent transversely to form a tuft having a loop, by the coöperative action of the needle and bristle carrier. The bristle carrier is then advanced to a point adjacent to said brush-stock, as shown in Figs. 15 and 100 16. The needle is then advanced in said bristle carrier and inserts the looped end of the tuft through the hole in said brush-stock and into the chamfered end of the tube, the bristles at this time remaining in the hole 110 in said brush-stock. The tube compressing dies are now brought into action and the tube compressed to bind the bristles therein and while said dies are engaging said tube the same is cut off from the remainder of 115 the tube adjacent to said loop. The dies are then retracted releasing the finished tuft which is supported in the hole in the brush-stock. The tube feeding means is returned to its alignment with the chamfering mechanism and by said movement a driver bar is 120 brought into alignment with said finished tuft and the hole in which it is located and forces said holder into the hole in said brush-stock occupied by said bristles, said hole 125 being shouldered to conform with the shape of said compressing holder. The driver bar is then retracted to the position shown in Fig. 14 and the brush-stock automatically fed or moved to bring the next successive 130

- hole therein into alinement with the tuft inserting mechanism and the parts are in position to duplicate the operation just described. At the conclusion of a predetermined number of insertions of bristle tufts in the brush-stock, as just described, the machine is automatically stopped, the brush-stock removed and a new one placed therein in readiness to be operated upon.
10. From the foregoing description, it will be seen that simple and efficient means are provided for accomplishing the objects of the invention, but while the elements herein shown and described are well adapted to serve the functions set forth, it is obvious that various minor changes may be made in the proportions, shape and arrangement of the several parts without departing from the spirit and scope of the invention as defined 20 in the appended claims.
- Having thus described my invention what I claim and desire by Letters Patent to secure is:
1. A brush making machine having, in combination, means for chamfering the inside of the end of a tube, a brush-stock holder, means for inserting a bunch of bristles through a brush-stock sustained in said holder and into said tube, means to compress said tube against said bristles to bind the same therein, and means to force said tube into said brush-stock.
  2. A brush making machine having, in combination, a brush-stock holder, means adapted to insert a bunch of bristles through a hole in a brush-stock sustained by said holder and into a tube, means for compressing said tube to bind the same therein, and means to force said tube into said hole.
  3. A brush making machine having, in combination, a holder adapted to sustain a brush-stock having a plurality of holes therein, means for doubling a set of bristles to form a tuft and to pass the end of said tuft through one of said holes and insert the same in a tube, means to compress said tube against said bristles to bind the same therein, and means to force said tube into said last mentioned hole.
  4. A brush making machine having, in combination, a holder adapted to sustain a brush-stock having a plurality of holes adapted to receive bristle tufts, means for doubling a set of bristles into a loop and inserting said loop through one of said holes and into a tube to form a tuft, means for compressing said holder against said bristles, means for forcing opposite portions of said tube into said loop, and means for forcing 55 said tube into the hole in said brush-stock in which said bristles are located.
  5. A brush making machine having, in combination, means to hold a mass of bristles, means adapted to remove a set of bristles 60 from said mass, means to hold a brush-stock,

said brush-stock having a plurality of holes extending laterally therethrough, means to bend said set of bristles to form a loop and insert said loop through one of the holes in said brush-stock and into a tube, means to force said tube into said last named hole, and means adapted to move said brush-stock holder to successively aline said holes with said loop inserting means.

6. A brush making machine having, in combination, a plurality of coöperating dies, means adapted to carry a tube between said dies, a holder for a brush-stock, said brush-stock having a plurality of holes therethrough, means to move said holder to aline said holes successively with said tube, instrumentalities to insert a set of bristles through the hole in alinement with said tube and into the end of said tube while the same is between said dies, means adapted to actuate said dies to compress said tube against said bristles, and means to force said tube into the hole in said brush-stock alining therewith.

7. A brush making machine having, in combination, a plurality of coöperating dies, means adapted to carry a tube between said dies, a holder adapted to sustain a brush-stock, said brush-stock having a plurality of holes extending therethrough, in close proximity to said dies with one of said holes in alinement with said tube, means to move said holder to bring said holes successively into alinement with said tube, instrumentalities to insert a set of bristles through the hole in alinement with said tube and into the end of said tube, means to actuate said dies to compress said tube against said bristles, and means to force said tube into the hole in said brush-stock alining therewith.

8. A brush making machine having, in combination, a plurality of coöperating dies, means adapted to carry a tube between said dies, a holder adapted to sustain a brush-stock, said brush-stock having a plurality of holes extending therethrough, in close proximity to said dies with one of said holes in alinement with said tube, means to move said holder to bring said holes successively into alinement with said tube, instrumentalities to insert a set of bristles through the hole in alinement with said tube and into the end of said tube, means to actuate said dies to compress said tube against said bristles, means to cut from said tube the portion containing said bristles, and means to force said tube into the hole in said brush-stock alining therewith.

9. A brush making machine having, in combination, a plurality of coöperating dies, means adapted to carry a tube between said dies, a holder adapted to sustain a brush-stock, said brush-stock having a plurality of holes extending therethrough, in close prox-

imity to said dies with one of said holes in alinement with said tube, means to move said holder to bring said holes successively into alinement with said tube, instrumentalities to insert a set of bristles through the hole in alinement with said tube and into the end of said tube, means to actuate said dies to compress said tube against said bristles, means to cut from said tube the portion containing said bristles, means to guide the cut off portion of said tube, and means to force said tube into the hole in said brush-stock alining therewith.

10. A brush making machine having, in combination, means to hold a brush-stock, said brush-stock having a plurality of holes extending laterally therethrough, means for inserting a bunch of bristles through each of said holes successively and into the end 15 of a tube, means to cut from said tube the portion containing said bristles, and means adapted to force the cut off portion of said tube into the hole in said brush-stock containing said bunch of bristles.

25. 11. A brush making machine having, in combination, a plurality of dies, a slide adapted to sustain a brush-stock, said brush-stock having a plurality of holes therein, means to clamp said brush-stock within said 30 slide with one of said holes in alinement with said tube, means to insert a bunch of bristles in the hole in said brush-stock alining with said tube and into said tube, means to actuate said dies to compress said tube on said 35 bristles, means to force said tube into said hole, and means adapted to move said slide to successively aline the holes in said brush-stock with said tube.

12. A brush making machine having, in combination, a support, a plurality of dies mounted on said support, means to present a tube to said dies, instrumentalities adapted to insert a bunch of bristles in the end of said tube, means to move said dies to 45 press said tube against said bristles, a brush-stock holder mounted in said support and adapted to sustain a brush-stock in close proximity to said dies, means to force said tube into said brush-stock, and means to 50 move said holder in said support transversely of said axis.

13. A brush making machine having, in combination, a support, a plurality of dies mounted in said support and adapted to be 55 moved therein to compress a tube, a brush-stock holder slide mounted in said support, a brush-stock holder slidably mounted in said holder slide, means to move said slide transversely of the axis of said support, means to 60 move said holder in said holder slide transversely of said axis and transversely of the direction of movement of said holder slide, means to present a tube between said dies, means adapted to insert a bunch of bristles 65 in said tube, means to actuate said dies to

compress said tube against said bristles, and means adapted to force said tube into a brush-stock sustained in said holder.

14. A brush making machine having, in combination, means for imparting a longitudinal feeding movement to a tube, means to guide said tube, means to chamfer the inside end of said tube, means to insert a set of bristles into the chamfered end of said tube, means to move said guiding and feeding means to present said tube first to the action of said chamfering means and then to said bristle inserting means, and means to insure the alinement of said tube with said chamfering means and said bristle inserting means respectively.

15. A brush making machine having, in combination, a holder for a brush-stock, said brush-stock having a plurality of holes therein, means to feed a tube to a point adjacent to said brush-stock and in alinement with one of said holes, a slide adapted to carry said tube feeding means, means to insert a set of bristles through said last named hole and into said tube, means carried by 90 said slide adapted to force said tube into said last named hole, and means to actuate said slide to alternately move said tube feeding means and said tube forcing means into alinement with said hole.

16. A brush making machine having, in combination, a support having a cylindrical guide opening extending laterally therethrough, a holder adapted to sustain a brush-stock having a plurality of holes extending 100 therethrough, means to move said holder to bring the holes in said brush-stock successively into alinement with said cylindrical opening, means to feed a tube to and into alinement with said cylindrical opening, instrumentalities adapted to form a tuft of bristles and insert the same through the hole in said brush-stock in alinement with said opening and into said tube, and means to force said tube through said guide opening 110 and into said last named hole.

17. A brush making machine having, in combination, a holder for a brush-stock, said brush-stock having a plurality of holes therein, means to feed a tube to a point adjacent to said brush-stock and in alinement with one of said holes, a slide adapted to carry said tube feeding means, means to insert a set of bristles through said last named hole and into said tube, means carried by 115 said slide adapted to force said tube into said last named hole, means to actuate said slide to alternately move said tube feeding means and said tube forcing means into alinement with said hole, and means adapted to 120 actuate said tube forcing means upon the alinement thereof with said hole.

18. A brush making machine having, in combination, a holder adapted to sustain a brush-stock, said stock having a plurality 130

- of holes extending therethrough, means adapted to form tufts of bristles and insert the same in said holes, means to secure said tufts in said holes, and means actuated by 5 the movements of said tuft forming means adapted to move successive holes in said brush-stock into alinement with said tuft inserting means.
19. A brush making machine having, in 10 combination, a holder for brush-stocks provided with a hole adapted to receive a tuft of bristles, instrumentalities adapted to form said tuft of bristles, means to force said tuft of bristles into a tube, means adapted to 15 move said tube forcing means into alinement with said tuft, and mechanism to lock said tube forcing means in said alined position and to actuate said forcing means.
20. A brush making machine having, in 20 combination, a holder for brush-stocks provided with a hole adapted to receive a tuft of bristles, instrumentalities adapted to form said tuft of bristles, means to force said tuft of bristles into a tube, means adapted to 25 move said tuft forcing means into alinement with said tuft, and mechanism to simultaneously lock said tuft forcing means in said

alined position and to actuate said forcing means.

21. A brush making machine having, in 30 combination, a holder provided with a recess adapted to contain a brush-stock, means to clamp said stock within said recess, instrumentalities adapted to form and insert a tuft of bristles into said stock with the end 35 of said tuft projecting slightly beyond the opposite face thereof, means to place a tube upon said projecting end, and means to move said tuft of bristles backwardly and force said tube into said hole. 40

22. A brush making machine having, in combination, means for holding a brush-stock, mechanism adapted to feed a tube to said brush-stock, mechanism to insert a tuft of bristles through said brush-stock and into 45 said tube, and means to insert said tube into said brush-stock.

In testimony whereof I have hereunto set my hand in presence of two subscribing witnesses.

DANIEL L. CHANDLER.
